UNITED STATES PATENT OFFICE.

WILLIAM H. BAKER, OF MONTREAL, QUEBEC, CANADA, ASSIGNOR TO F. WILSON FAIRMAN, OF MONTREAL, CANADA.

LOOM.

Original application filed December 17, 1921, Serial No. 523,140. Divided and this application filed October 21, 1925. Serial No. 63,889.

This invention is a division of that originally presented in the parent application for U. S. Letters Patent filed by me December 17, 1921, Serial No. 523,140. The general aim in the present instance, as also in the case of the subject-matter of the said parent application, is to enable the speed and efficiency of existing and new looms to be increased materially as compared with the speed and efficiency heretofore attainable in practice. This aim is accomplished by eliminating the destructive concussive shocks which in looms constructed as heretofore usual in practice are incidental to the action of the mechanism employed for arresting the lay of a loom in its beating-up movement, and stopping the loom, in case the shuttle fails to enter properly into a shuttle-box at the end of a flight of the shuttle across the loom. Other related improvements having the same aim and along the same line have been presented and claimed in Letters Patent No. 1,532,667 and No. 1,532,668, granted to me under date of April 7, 1925 upon applications filed subsequent to the said original application. The present invention is differentiated from the said improvements in the respect which is indicated hereinafter.

In all power looms it is necessary to provide some means of protecting the warp threads from the damage which would result if the lay should beat up with a shuttle lying partly or wholly in the shed (in the warp threads) through which it has just traveled, in consequence of having only partly entered into a shuttle-box at the end of a flight across a loom, or having failed to box at all. In fast reed looms this protection is obtained through the employment of means to effect an instantaneous arrest of the lay in its beating-up movement, at an intermediate point in such movement, if the shuttle is not properly boxed. Such means consists of the wellknown protector-mechanism, the latter including a so-called frog on the frame of the loom, and an engaging member on the lay, constituted by a so-called dagger which is normally positioned to strike the frog and having connected therewith parts by means of which it is moved into non-striking or non-engaging position by the shuttle when the latter

boxes properly at the end of a flight across the loom. It has been proposed, also, to bring about slackening of the warp concurrently with the arrest of the lay by the protector-mechanism.

The sudden and positive arrest of the lay which is effected by the means usually employed heretofore in practice for the purpose, such arrest involving also arrest of the other working parts of the loom, subjects the loom mechanism and loom frame to very great shocks and stresses, with the result that breakages occur frequently. The shock and stresses increase in force and degree with the speed of the loom, by reason of which fact there is a limit to such speed, determined by the specific character of the protector-mechanism and the ability of the loom mechanism and frame to withstand shock and stresses. If the speed limit is exceeded the breakages increase in frequency, necessitating discontinuance of the use of the loom, and repairs, thereby reducing production and creating incidental cost, and also increasing the rate at which the loom deteriorates.

In the case of the present invention, as in that of the subject-matter of Letters Patent Nos. 1,532,667 and 1,532,668, aforesaid, the organization which acts to protect the warp threads from smashes is so constituted, etc., that instead of the positive concussive arrest of the lay, with destructive tendencies, which occurs in looms equipped with the dead stop protector-mechanisms which heretofore have been employed in usual practice, the momentum of the forwardly-moving lay is absorbed yieldingly and thereby the lay is brought to rest yieldingly before completion of the beating-up movement; at the same time the warp is slackened. As in the two Letters Patent, the slackening of the warp is brought about by movement given to a warp-guide, with which the warp engages on its way from the warp-beam.

By the employment of mechanism acting as just described, it is rendered entirely safe and practical to run a loom at a considerably higher rate of speed than heretofore safely possible.

Having reference now more particularly to the distinguishing characteristic of the present invention, it will be observed that

in the case of the constructions illustrated and described in the two Letters Patent which have been referred to the frogs of the protector-mechanism are connected to oppositely located levers which are mounted fixedly upon opposite ends of a rockshaft extending across the loom, the fixed mounting of the two oppositely-located levers upon the said rockshaft serving to connect the two levers rigidly together so that they occupy definite relations to each other and move in exact unison to the same extent. In the case of the present invention separate control-members which are not connected positively with each other are employed, they preferably being levers, though not necessarily in all instances. The relative independence of the two control-members or levers in respect of movement secures for them greater flexibility and conformability to the conditions and working of the parts which are employed at the two sides of the loom, and brings more equally into play, in the protecting action, the dagger and frog devices at the two sides of the loom. Another advantage is mentioned hereinafter.

Accordingly the invention presents, in a loom, the combination with a moving lay, a protector-mechanism including shuttle-controlled engaging elements moving with the lay, and a warp-guide with which the warp engages on its way from the warp-beam, of control-members which are not connected positively with each other, located opposite each other laterally of the loom, and movement-resisting means combined with the individual control-members adapted to absorb yieldingly the momentum of the lay in the beating-up movement and thereby bring the lay to rest yieldingly before completion of such movement, with the individually movable control-members correlated with opposite ends of the warp-guide to produce warp-slackening movement of the warp-guide.

An illustrative embodiment of the invention is shown in the accompanying drawings, in which,—

Fig. 1 shows in side elevation portions of a double vertical loom with the said embodiment incorporated therewith.

Fig. 2 shows portions of such loom in front elevation, the lay being somewhat lower than in Fig. 1.

Fig. 3 shows in plan portions of the stopping instrumentalities of the loom.

The loom mechanism in general is not involved in the invention, nor is it material whether the invention itself is applied in connection with an upright or vertical loom as in the accompanying drawings, or in connection with looms of usual type.

Having reference to the drawings, portions of the opposite end frames of a loom

are shown, 11, 11, being the lower parts of said end frames, and 12, 12, being portions of the upper parts thereof. 13 is a driving pulley mounted on a jackshaft 16, the latter being connected by gearing 20, 21, to the 70 crankshaft 25, the cranks of which are connected by pitmen 39, 39, with the lay swords 37, 37, the latter being mounted upon the lay rockshaft 31. At 38 is a lay beam connected with the lay swords, 37, 37. The 75 shuttle boxes at opposite ends of the lay beam are designated 46, 46. Through the mechanism described the lay is actuated, its movement being in this instance in a vertical arc, as usual in upright or vertical 80 looms, instead of being in a substantially horizontal arc as in ordinary looms. The driving of the loom through the medium of the friction pulley 13 is controlled by means of a clutch-lever 17, the said clutch-lever being connected with an adjacent shipper-handle 32 at that end of the loom at which the clutch-pulley is located by means of a link 36 extending from the lever to a crank arm 331 upon the shaft 33 of the shipper-handle, the 85 said link 36 and crank arm being arranged to operate after the fashion of a toggle, as common in shipper mechanism for looms and other machinery. By movement of the said adjacent shipper-handle 32 in one direction, 90 namely from right to left into the position occupied by it in Fig. 2, the shipper-lever 17 is operated to render the friction pulley 13 operative for the driving of the crank shaft and loom; through the movement of the shipper-handle in the opposite direction, namely from left to right, the driving is discontinued. A second shipper-handle 32 is mounted upon a rock shaft 34 at the opposite ends of the loom, for convenient use 95 by the weaver when standing at or near such end, arms upon the two rockshafts 33, 34, being connected by a rod 35 so that the two rockshafts and shipper-handles turn in unison, and the clutch-lever 17 may be actuated by similar movements of either shipper-handle.

A warp-beam is shown at 59, and at 61 is shown a warp-guide with which the warp, indicated by dotted line in Fig. 1, engages on its way from the warp-beam to the weaving instrumentalities of the loom. Loom harness is indicated at 50, 49 being a harness-supporting roll, and 72, Fig. 1, is a breast-roll partly around which the cloth as 105 woven passes on its way to the cloth-roll 62.

The parts thus far referred to are merely features of the loom in general.

The drawings show protector-mechanism comprising as usual a protector-rockshaft 125 821 mounted in connection with the lay and provided at its opposite ends with protector-fingers 82 adapted to be operated on the entrance of a shuttle into either shuttle-box to rock the protector-rockshaft 821 in one di- 130

rection. As usual the protector-rockshaft is yieldingly actuated so that the protector fingers tend normally to approach the interior spaces of the shuttle-boxes. Through the 5 entrance of the shuttle into either shuttle-box, action in connection with the corresponding protector-finger 82 presses the fingers away from the spaces of the shuttle-boxes so as to rock the protector-rockshaft 10 821 in the opposite direction. The protector-mechanism includes engaging elements 80, 80, which are mounted pivotally in connection with the lay and in this instance are engaged by arms 81 fixedly attached to the 15 protector-rockshaft 821, so that the said engaging elements 80, 80, constitute shuttle-controlled engaging elements moving with the lay. In the present instance the said 20 engaging elements 80, 80, are in the form of hooks that are adapted to engage with hooks 79, 79, upon rods 78, 78, in connection with the control-members 75, 75. The action corresponds closely with that of usual protector-mechanism; namely, whenever a shuttle 25 is fully entered into either shuttle-box the protector-rockshaft is actuated thereby, the said rockshaft being rocked so as to bring about movement of both engaging members 80, 80, into positions in which they 30 will not engage with the hooks 79, 79, in the upward swinging movement of the lay. When, however, the shuttle fails to enter either shuttle-box at the end of a flight 35 across the loom, or is not entered into one of the shuttle-boxes far enough to operate the corresponding protector-finger 82, the engaging members 80, 80, remain in position 40 to engage with the hooks 79, 79, and in the beating-up movement of the lay hooks 80, 80, engage with the hooks 79, 79, and as a result of such engagement draw the rods 45 78, 78 in the direction in which the lay is moving at the time, namely upward. 50 In this instance the control members 75, 75, are in the shape of bell-cranks which are mounted in connection with the lower parts 55 11, 11, of the end frames of the loom. Each bell-crank has connected therewith one extremity of a powerful spring 76. By the 60 tension of the respective springs 76 the individual bell-cranks are held normally from movement, and by such tension the movement of the lay is opposed as soon as the 65 hooks 80, 80, have taken hold of the hooks 79, 79. One advantage of employing separate control-members at the opposite sides of a loom is that thereby it is rendered practicable to locate the places of support for 70 such members within the diameter of the heads of the warp-beam, as in the drawings, when the circumstances make such location desirable. This secures greater compactness and in some instances permits a simpler and 75 more advantageous disposition of parts, as well as a less expensive construction, than

when the control-members are fixed upon the opposite ends of a rockshaft extending across the loom.

For warp-slackening purposes, the warp-guide 61 is actuated by the control-levers 70 75, 75, in the short movement of the latter in unison with the lay before the beating-up movement of the lay is terminated by the resistance offered by the springs 76, 76. In the present instance the warp-guide is supported by the control-levers through having end-journals thereof entered into slotted bearings with which the control-levers are provided. Preferably I employ springs 76, 75, 80, of power-proportioned to enable the warp-guide to operate after the manner of a spring-controlled whip-roll.

In usual practice the protector-mechanism of a loom is combined and arranged to throw off the driving power of the loom and arrest the action of the loom when the protector-mechanism acts on detection of failure of the shuttle to enter properly into one of the shuttle-boxes. In the case of the loom that is partly shown in the drawings, each rod 78 carries a projection 79^a, which, as the rod 78 is pulled lengthwise upward as a result of the engagement of the adjacent hook 80 with the hook 79 of the rod, is carried against a finger 79^b projecting from the rockshaft 33 or 34 of a shipper-handle 32, the result of which is rocking of the shipper-handle rockshafts and movement of the shipper-lever 17 by which the driving power is thrown off.

What is claimed as the invention is,—

1. In a loom, the combination with a moving lay, protector-mechanism including shuttle-controlled engaging elements at both sides of the loom moving with the lay, and a warp-guide with which the warp engages on its way from the warp-beam, of individual control-members which are located opposite each other laterally of the loom without positive connection with each other, and actuated by means of said shuttle-controlled engaging elements and movement-resisting means combined with the individual control-members adapted to absorb yieldingly the momentum of the lay in the beating-up movement and thereby bring the lay to rest yieldingly before completion of such movement, with the individually movable control-members correlated with opposite ends of the warp-guide to produce warp-slackening movement of the warp-guide.

2. In a loom, the combination with a moving lay, protector-mechanism including shuttle-controlled engaging means moving with the lay, and a warp-guide with which the warp engages on its way from the warp-beam, of individual control-levers which are located opposite each other laterally of the loom without positive connection with each other, and adapted respectively to be actu-

ated through the agency of said shuttle-controlled engaging means and movement-resisting means combined with the individual control-levers adapted to absorb yieldingly 5 the momentum of the lay in the beating-up movement and thereby bring the lay to rest yieldingly before completion of such movement, with the individually movable control-levers correlated with opposite ends of 10 the warp-guide to produce warp-slackening movement of the warp-guide.

3. In a loom, the combination comprising a moving lay, protector-mechanism including shuttle-controlled engaging elements 15 moving with the lay, whip-roll devices including a warp-guide with which the warp engages on its way from the warp-beam and levers combined with the opposite ends of said warp-guide, said levers movable independently of each other, whereby through 20 actuation of the levers individually by the said engaging means the whip-roll is operated to slacken the warp, and movement-resisting means combined with the respective 25 levers and acting through the latter individually to arrest the beating-up movement of the lay before completion thereof by absorbing yieldingly the momentum of the lay, simultaneously with the slackening 30 of the warp.

4. In a loom, the combination with a moving lay, protector-mechanism including shuttle-controlled engaging elements moving with the lay, and a warp-guide with which 35 the warp engages on its way from the warp-beam, of individual control-members located opposite each other laterally of the loom

with the places of support for such members within the diameter of the heads of the warp-beam, said control-members 40 adapted respectively to be actuated through the agency of said engaging elements, and movement-resisting means combined with the individual control-members adapted to absorb yieldingly the momentum of the lay 45 in the beating-up movement and thereby bring the lay to rest yieldingly before completion of such movement, with the individually movable control-members correlated with opposite ends of the warp-guide 50 to produce warp-slackening movement of the warp-guide.

5. In a loom, the combination with a moving lay, protector-mechanism including shuttle-controlled engaging elements moving with the lay, and a warp-guide with which the warp engages on its way from the warp-beam, of individual control-levers located opposite each other laterally of the loom with the pivotal supports therefor situated within the diameter of the heads of the warp-beam, said control-members adapted respectively to be actuated through the agency of said engaging elements, and movement-resisting means combined with the individual control-levers adapted to absorb yieldingly the momentum of the lay in the beating-up movement and thereby bring the lay to rest yieldingly before completion of such movement, with the individually movable control-levers correlated with opposite ends of the warp-guide to produce warp-slackening movement of the warp-guide. 60 65 70

WILLIAM H. BAKER.
